RAY HOFFMAN, OF NEWPORT, KENTUCKY, ASSIGNOR TO NATIONAL MARKING MACHINE COMPANY, OF CINCINNATI, OHIO.

LAUNDRY-MARKING CLIP.

1,349,570.

Specification of Letters Patent. Patented Aug. 17, 1920.

Application filed October 6, 1919. Serial No. 328,892.

To all whom it may concern:

Be it known that I, RAY HOFFMAN, a citizen of the United States, and a resident of Newport, in the county of Campbell 5 and State of Kentucky, have invented a certain new and useful Laundry-Marking Clip, of which the following is a specification.

The object of my invention is to provide a laundry marking clip of simple, durable 10 and inexpensive construction.

A further object of my invention is to provide a clip, which may be secured to laundry by the launderer to distinguish an article which cannot be marked with ink, 15 so that after it has been washed, it may be placed with the proper customer's bundle.

A further object of my invention is to provide such a clip, which is adapted to be readily attached to the goods or fabric of 20 washable articles and which will not damage these goods.

A further object of my invention is to provide a clip, comprising a readily removable portion and a permanent portion designed 25 to receive a customer's mark or other symbol so that the temporary portion of the clip may be changed from time to time, as it becomes worn or unserviceable, with a comparatively slight expense. In this connection, it may be mentioned that it has been the custom to use metal for markers 30 for laundry, which is flexible, so that the metal may be bent over the laundry, and its resistance after being bent will hold it 35 firmly secured to the laundry. It has, however, not been found practical to remove these clips from the laundry, so that they have been a source of continual expense. Detachable clips of more permanent material 40 are uncertain because they have been in the past too heavy and are likely to tear the goods, besides being extremely difficult to remove, and of course the expense made it unadvisable to leave these clips upon the 45 goods when they were sent to the customers.

My invention comprises a combination between the two old systems, which combines the advantages of each without their disadvantages by using in connection with 50 a comparatively stiff metal body member of somewhat resilient material, a goods holding flap of flexible and very slightly resilient material, which may be pressed against the body member to grip the goods.

With these and other objects in view, my 55 invention consists in the construction, arrangement and combination of the various parts of the device, whereby the objects contemplated are attained, as hereinafter more fully set forth, pointed out in my 60 claims, and illustrated in the accompanying drawings, in which:

Figure 1 shows a back view of my improved clip.

Fig. 2 shows a front view of the same. 65

Fig. 3 shows a longitudinal, central, sectional view therethrough.

Fig. 4 shows a side elevation of the clip.

Fig. 5 shows a plan view of the blank from which the permanent portion of the 70 clip is made; and

Fig. 6 shows an end view of the device.

Referring to the accompanying drawings, I have used the reference letter "A" to indicate generally the blank from which my 75 improved clip is made, which comprises a portion 10 having a central opening 11 therein and a somewhat pointed tongue 12 punched out at one end, so that the tongue will project somewhat upwardly from the 80 surfaces of the body member, as is shown in Fig. 3.

Extending laterally from the body portion 10 of the blank are side members 13, which terminate in tongues 14. The blank 85 may or may not be creased on the dotted lines 15 for folding purposes. On the back of this blank is printed or impressed a numeral, indicated by the reference numeral 16, which will of course be varied so that 90 when the tag is attached to articles belonging in different bundles, then the number will distinguish which articles belong in which bundles.

A slot or perforation 17 is formed at the 95 upper end of the body portion 10, and is adapted to receive a hook or the like, whereby the laundry article to which the tag is secured, may be suspended from the hook.

The body portion 10 is preferably formed 100 from a somewhat resilient metal, such as aluminum or brass, and should be such that washing compounds or the like will not cause corrosion that would possibly stain the garments to which the tag is attached. 105

An auxiliary fastening piece or flap "B" is formed from any suitable material, having for instance the properties of zinc, and

is provided with a round opening 18 at one end, and a substantially square opening 19 adjacent to the other end. The opening 18 is designed to permit the tongue 12 to extend up into it, so that when the flap "B" is pushed down against the body 10, then the tongue 12 will serve to hold the goods between the flap and body 18, and thereby prevent accidental displacement of the tag. 5 It will be noted that the opening 18 is of such size, it clears the tongue 12 by an appreciable distance, so that the goods which are being washed will not be tightly squeezed between two metal surfaces, as that would 10 cause a black place on the goods, where it was so gripped.

The opening 19 is designed to receive the tongues 14 of the blank "A", whereby the flap "B" may be held against the body portion 10. For accomplishing this result, the extensions 13 are bent up over the flap "B", and the tongues 14 are extended through the openings 19 and 11, and the protruding ends 14^a are bent against the body 10, so 25 that the tongues 14 may not spring away from the flap "B" and permit it to spring away from the body portion 10.

The use of flexible material, such as zinc, in the flap "B" has a double purpose. The 30 free end of the flap may be bent between the ends readily to position where the tongue 12 will enter the opening 18 for a considerable number of times without injuring the material of the flap, so that the clip may be used to fasten to a number of garments successively.

Moreover if the flap "B" were made out of resilient material, it would have to be constructed so that the resiliency of the 40 material would tend to force it against the body portion "A" thereby causing a portion of the garment 20 to be under compression, so that that portion would not be thoroughly washed.

45 When, however, the zinc flap "B" is pressed down against the body portion 10, its resiliency is just sufficient, so that it will engage the garment 20 some, but not enough to entirely prevent water from penetrating 50 into the garment between the flap and body portion. Moreover it will be seen that the pressure of the hand will naturally be somewhat toward the end of the flap "B", so that the central portion of the flap between 55 the tongues 14 and the opening 18 will be somewhat bowed and therefore spaced from the body portion 10, which will permit water to enter between the body portion 10 and the flap, and permit the garment to be 60 cleansed adjacent to the clip, almost, if not fully as much, as the remaining portion of the garment is cleansed.

65 The use of the tongue 12 also in connection with the opening 18 is such that water may be forced by the washing process

through the opening 18 around the tongue 12, thereby permitting the portion of the garment to be cleansed.

In fact, experiments with this type of clip have shown that it is almost, if not entirely, impossible to tell where the clip has been fastened to a garment after the latter has been washed.

In this connection, special attention is directed to the shape of the tongue 12 and the manner in which it is formed. I find that an ordinary pointed tongue projecting upwardly from the body member into the opening 18 is somewhat likely to tear the goods when an article is being removed from the clip. The tongue, which I have provided, is therefore so shaped that even though the goods should be accidentally torn out of the grip, it would be highly improbable that the goods would be torn, due to the shortness of the tongue 18.

I preferably form my tongue 12 by forcing the sharp pointed tool against the upper surface of the body member 10 with the axis of the tool inclined relative to the surface of the body member, so that the point of the instrument will enter the material of the body member and form a recess therein. The pushing of the instrument into the material of the body member raises up the tongue 12 to substantially the shape shown in Fig. 3, and forms the tongue, so that the side thereof opposite the central portion of the body member will be inclined upwardly and toward the said central portion. 100

It is also of such shape that if the garment is to be pulled out of the clip, it would be almost impossible to tear the fabric by its contact with the tongue.

An advantage of my improved construction resides in the fact that I provide a clip, which may be made entirely by punch presses and dies, whereby the cost of production is minimized.

A further advantage resides in the use of the zinc flap "B", which is flexible rather than resilient, and which makes it possible to wash the garment where the clip is fastened to it; besides making it easier to attach and detach the clip relative to the garment. Other metals may be substituted for the zinc, such for instance, as soft brass, the limitation being that the material of the flap must be flexible rather than resilient. The bending or flexible portion of the clip, 115 namely the flap "B", may be also readily replaced at a comparatively small expense, but is adapted to be used for a number of washings without being changed.

A further advantage of my invention resides in the fact that I have provided a clip, which may be used to mark articles a considerable number of times, and which may be readily attached or detached to the garment. In this connection, it should be 130

noticed that where two jaws of this comparatively stiff resilient material are used for gripping garments, which are washed, then the person who removes these clips 5 from the garments after the latter are washed, must either use a tool for the removal or else must exert a considerable effort with the hands to spread the jaws.

Where a grip is used, which comprises 10 two parts or jaws of flexible material, such as zinc, the clip is not sufficiently rigid, and again difficulty is encountered in removing the clip, due to the pliable nature of the material of the jaws.

Where, however, my invention is used, the comparatively rigid body portion may be 15 firmly grasped with little or no trouble and then the garment may be removed by pulling it in the proper direction to pull the flap up to the position shown in dotted lines 20 in Fig. 3; or the end of the flap projecting beyond the opening 18 may be caught by the fingers of the operator and raised.

A further advantage resides from the use 25 of the flexible flap member "B," in that the central portion thereof after it has once been bent away from the body member 10 will be bowed upwardly and away from the central portion of the body member 10, thereby permitting free access to the washing 30 water, so that the edge of the garment between the parts of the clip will be thoroughly cleansed. The tongue 12 is also of such size and so placed relative to the opening 35 18 that it will press the goods up against the edges of the opening and will project into the fibers of the goods, just sufficiently to keep them from sliding over the end of the tongue when it is forced upwardly into 40 the opening 18. This structure, it will be noted, does not cause the cloth to be squeezed between the two metal portions thereby making it extremely unlikely that the cloth 45 will be stained and making it possible to wash the cloth throughout.

Some changes may be made in the construction and arrangement of my improved device without departing from the real purpose and spirit of my invention, and it is 50 my intention to cover by my claims any modified forms of structure or use of mechanical equivalents, which may be reasonably included within their scope.

I claim as my invention:

1. In a device of the class described, a laundry holding clip comprising a body portion having a central opening and laterally projecting extensions at either side, and a flap member of flexible material having an 55 opening adjacent to one end whereby the ends of the extensions may be folded over upon the flap member and extended through the said opening to hold the flap member from movement relative to the body member.

2. In a device of the class described, a laundry holding clip comprising a blank of resilient material having central openings, lateral extensions at either side and a tongue extended outwardly from the face thereof 70 adjacent to one end, and a flap member of flexible material having an opening at either end, one of said openings being designed to receive said tongue and the other opening being designed to receive said extensions, 75 whereby the flap member may be secured to the body member.

3. In a device of the class described, a laundry holding clip comprising a blank 80 formed from sheet metal, having a body portion with a central opening and an upper slot and a tongue extending from its surface adjacent to the lower portion, said body portion having extensions at either side and a flap member having openings adjacent to 85 either end, one of said openings being designed to receive the tongue and the other opening being designed to receive said extensions, whereby the latter may be folded upon the body portion of the blank and ex- 90 tended through the central opening thereof and the flap to hold one end of the latter from movement relative to the body portion.

4. In a laundry holding clip adapted to 95 receive and be attached on the articles to distinguish the articles of the bundle of one customer from those of another bundle, a body member of comparatively rigid material, and a flap member of flexible and sub- 100 stantially non-resilient material having one end thereof secured to one end of the body member, whereby the free end of the flap member may be moved selectively toward and from the body member to engage and disengage laundry articles, the flap member being so disposed relative to the body member that its free end is disposed between the adjacent end of the body member and the fixed end of the flap member.

5. In a laundry holding clip adapted to 110 be detachably mounted upon laundry articles, a body member of comparatively stiff resilient material, and a flap member of flexible but comparatively non-resilient mate- 115 rial, having one end secured to the body member whereby articles may be selectively engaged and released by the clip by moving the free end of the flap member toward and from the body member, and means formed 120 integral with the body member adapted to receive a laundry supporting hook fixed in a laundry marking clip, a body member of comparatively stiff resilient material having a tongue raised from its surface adjacent to 125 one end, and a flap member of flexible but comparatively non-resilient material having one end secured to the body member in position spaced from the tongue and having an opening in the second adapted to receive 130

the tongue when the free end of the flap member is in position substantially parallel with the body member.

6. In a laundry holding clip adapted to be attached to and frictionally engage articles to be laundered, a body member of comparatively stiff resilient material, which is not adapted to be flexed by the hands of an operator, and a flap member of flexible comparatively non-resilient material adapted to be flexed by the operator, said flap member having one end secured to the body member whereby the free end of the flap member may be moved by the hand of the operator selectively toward and from the body member to engage and disengage laundry articles.

7. In a laundry holding clip adapted to receive and engage articles to be laundered, whereby the articles of one customer may be distinguished from those of another customer after they have been washed, a body member of comparatively stiff, resilient material, which is not adapted to be readily flexed by the hands of the operator, said body member having a tongue extended upwardly from one of its surfaces adjacent to one end, the side of the tongue adjacent to the other end of the body member being inclined upwardly and away therefrom, and a flap member of flexible and comparatively non-resilient material adapted to be flexed

by the hands of the operator having one end secured to the second end of the body member, said body member having an opening adjacent to its free end, whereby the said end of the flap member may be moved selectively toward and from the body member to engage and disengage laundry articles, the tongue and opening being so arranged that the former will enter the opening when the flap member is moved to position adjacent to the body member, but will not offer projecting corners, which will tear the fabric when the latter is pulled out from between the flap member and body member.

8. In a laundry holding clip adapted to receive and be attached on the articles to distinguish the articles of the bundle of one customer from those of another bundle, a body member of comparatively rigid material, and a flap member of flexible material having one end thereof secured to one end of the body member whereby the free end of the flap member may be moved selectively toward and from the body member to engage and disengage laundry articles, the flap member being so disposed relative to the body member that its free end is disposed between the adjacent end of the body member and the fixed end of the flap member.

Des Moines, Iowa, September 17, 1919.
RAY HOFFMAN.
